KEY HOLDER

Joseph J. Pentek, San Carlos, Calif.

Application March 13, 1950, Serial No. 149,250

2 Claims. (Cl. 70—456)

1

This invention relates to key holders, and more particularly to improvements in that type of key holder which comprises a case, a key carriage slidably disposed therein, and spring means for the carriage adapted to retract the carriage and key carried thereby within the case when the key becomes slidably movable within the key barrel of a lock.

In summary, the invention resides, in part, in that improvement in a device of the class above mentioned enabling the latching of a key carriage in its forward position within the case, i. e., so that the key extends outside of the case, whereby the key may be manipulated with respect to the lock with a minimum of effort, since the key is secured against retractile movement within the case, with said latching means being operable upon the application of a pulling force to the key tending to remove the key further from the case, as, for example, when the key is pulled outwardly of a lock, to release the key carriage and allow the same to be retracted rearwardly into the case to enclose the key therein. Additional improvements reside in the provision of a key case comprised of complementary sections, with the guide slot for the thumb contactable button of the carriage being formed by the complementary edges forming a side of each of the case sections, and, further, the provision of means enabling the ready securing of a key to the carriage after the carriage has been assembled and enclosed within the case of the holder, said means comprising an aperture in the carriage alignable with an aperture through the wall of the case to enable the introduction of an attachment stud through the case aperture and into the carriage aperture to secure a key to the carriage.

Further details of the invention will be apparent from the following description taken in conjunction with the drawings forming part of this specification, and in which:

Figure 1 is a view in side elevation of the key holder embodying the invention;

Figure 2 is a view in side elevation of the key holder with the top section of the case removed;

Figure 3 is a view in section taken along lines 3—3 of Figure 2, but showing the key to carriage fastening means in place;

Figure 4 is a view in side elevation showing the inside of the top section of the key holder case;

Figure 5 is a view in bottom elevation of the key holder of Figure 1; and

Figure 6 is a view in section taken along lines 6—6 of Figure 1.

2

Referring to the drawing for more details of the invention, the key holder comprises a bottom case section 10 and a top case section 12 complementary thereto. The bottom case 10 is characterized by a pair of oppositely disposed semi-wells 14, an elongate recess 16 at the inside of the upper side wall, an upstanding guide rib 18 extending around the rearward portion of the side walls of the case section and serving as positional attachment means for the top case section 12, a boss 20 having a rivet aperture 22 therethrough, a box-like rib structure 24, an elongate groove 26, an aperture 28 through the wall of the case, a smaller aperture 30 for key chain attachment purposes, and cleats 32 serving in conjunction with the rib 18 to positionally secure the case sections 10 and 12 together when they are juxtaposed.

A key carriage indicated generally at 34 is slidably disposed within case section 10 and a spring 36 secured at one end as by a rivet 38 to the carriage and having a loop at its other end in sleeved relation to the boss 20 serves to yieldingly retain the carriage in the position shown in Figure 2. The bottom case and carriage assembly, before the attachment to the bottom case of the top case section 12, further comprises a coil spring 40 clipped over the forward side of the box-like structure 24 so that the rearward end of the spring is within the box-like structure and the forward end extends forwardly thereof to serve as a resilient bumper when the carriage 34 is retracted by the spring 36 to the position of Figure 2. The lower side wall of case section 10 is provided with a relatively deep notch 42 within which a latching stud 44 is fitted so that the enlarged inner end 46 of the stud prevents axial withdrawal of the stud from the notch 42. A spring 48 sleeved on the shank of stud 44 and in contact with the under side of the head of the stud and the outer surface of the case section 10 serves to maintain the stud in a retracted position with respect to the interior of the case section.

The bottom case and carriage assembly, as thus described, is converted to the complete key holder by the attachment thereto of the top case section 12, said latter section comprising semi-wells 50 complementary to the semi-wells 14 of the bottom case section 10, a boss and aperture 52 and 54, respectively, complementary to the corresponding elements 20 and 22 of the bottom case section, an aperture 56 complementary to the aperture 30 of the bottom case section, an elongate groove 57, and an aperture 58 through

the wall of the top case section adapted to be in alignment with the corresponding aperture 28 of the bottom case section when the sections are secured together in complementary relation. The case section 12 is also provided with a nib-like member 60 adapted to be received within the notch 42 of the bottom case section when the two case sections are placed in complementary relation to retain the stud 44 against any appreciable lateral movement.

When the top case section is juxtaposed to the bottom case section 10, any forward motion by way of slippage of the section 10 with respect to the section 12 is prevented by the rib 18, while any rearward slippage of the section 12 with respect to the case 10 is prevented by the cleats 32 which fit within the case at positions indicated by 62 in Figure 4. Rivets 64 are then passed through the aligned semi-wells 14 and 50, and aligned apertures 22 and 54, and these rivets are then upset to secure the case sections together. When the sections are so secured together the bosses 20 and 52 are in engagement with each other, thus preventing the spring 36 from working free of the boss 20 during operation or use of the key holder. A suitable attachment chain, not shown, may be passed through the aligned apertures 30 and 56.

As indicated by Figures 1-3, the carriage 34 is provided with a thumb knob or button 66, integral with the carriage proper through the neck or reduced section portion 68, slidably within the slot formed by the elongate recess 16 of case section 10 and the adjacent edge of case section 12. A rib 70 at one side of the carriage and a boss 72 of the other side thereof serve as means for guiding the movement of the carriage with respect to the case. The carriage is also provided with an aperture 74 adapted to receive a screw 76, and a hexagonal recess 78 in one side of the carriage adapted to receive a nut 80 for the securing of the screw 76 to the carriage. The head of the screw 76 is slightly smaller than the aperture 58 and registrable therewith by a slidable positioning of the carriage 34 within the case, while the hexagonal recess 78 is similarly registrable with the aperture 28 of case section 10. A key 82 may be secured to the carriage 34 after the key holder is fully assembled by the simple expedient of sliding the carriage to align the screw 76 and nut 80 with their respective case apertures 58 and 28; unfastening the screw and removing the same; inserting the head of a key within the mouth of the case against the side surface 84 of the carriage to align the aperture of the key with the case apertures 28 and 58 and the carriage aperture 74, and re-engaging the screw 76 with nut 80. The elongate recesses 26 and 51 are for the accommodation of the head of screw 76 and for the outer portion of nut 80 which protrudes slightly from the face of the carriage.

From the foregoing description it will be clear that the key 82 may be inserted within the ignition switch of an automobile, for example, by applying the thumb to the button 66 and forcing the carriage 34 forwardly in the case against the action of spring 36 to unsheathe the key. Upon insertion of the key within the ignition switch and the turning of the switch to the "on" position the engagement of the key in the lock will prevent spring urged withdrawal of the key within the case. When the key is turned in the ignition switch to move the switch to the "off" position, the key is then relatively freely slidably movable in the lock and the spring 36 then serves

to withdraw the key from the ignition switch, with the force of the spring urged return of the carriage within the case being absorbed by the spring 48.

When the carriage has been moved forwardly to unsheathe the key to a sufficient degree so that the rearward end 86 of the carriage is located slightly forwardly of the stud 44, the stud 44 may be urged inwardly of the case against the action of spring 48 to become engaged with the rearward edge of the carriage and prevent the spring urged return of the same. The force of spring 36 tending to return carriage 34 within the case as applied transversely to the axis of stud 44 is sufficient to prevent the spring 48 from withdrawing the stud from its latching position with respect to the carriage. The case then serves in effect as a fixed carrier or handle for the extended key, enabling a ready and efficient manipulation of the key with respect to the lock. When the carriage is in this latched condition and the ignition switch is turned to the "off" position, the spring 36 will not be effective to retract the key from the lock. However, when the case is grasped and pulled toward the operator to remove the key from the lock, the frictional engagement between the lock and key is normally such as to enable a slight rearward movement of the case before the withdrawing movement of the key takes place. This serves to move the carriage 34 forwardly of the stud 44, thus freeing the stud 44 for retraction from the return path of the carriage by means of the spring 48. When this has occurred, the spring 36 will snap the carriage 34 and key 82 carried thereby into sheathed relation with the case.

While a preferred embodiment of the key holder of the invention has been shown and described, it is to be understood that all substantial equivalents of said embodiment are within the scope of the invention.

What I claim as new and desire to secure by Letters Patent is:

1. A key holder comprising a case having an opening at its forward end, a key carriage slidably disposed therein and having a manual control member extending through a guide slot formed in the case, a spring forming a connection between said carriage and said case operable to urge said carriage rearwardly in the case; catch means carried by the case and adapted to be moved inwardly into the path of movement of said carriage after said carriage has been slidably moved forwardly of said catch means toward the open end of said case to retain said carriage against rearward movement by said spring, and spring means associated with said catch means and said case operable to move said catch means out of the path of said carriage in response to a further forward movement of said carriage to bring said carriage out of engagement with said catch means.

2. A key holder comprising a case having an opening at its forward end, a key carriage slidably disposed therein and having a manual control member extending through a guide slot formed in the case, a spring forming a connection between said carriage and said case operable to urge said carriage rearwardly in the case, a member extending through said case and carried by said case for limited movement transversely of the path of movement of said carriage, said member being operable upon its movement inwardly of said case after said carriage has been yieldingly urged forwardly of said member to

ward the open end of said case to block rearward movement of said carriage therepast, the spring-pressed engagement of said carriage with said member serving to retain said member in such carriage-blocking position, and spring means for said member operable when the spring pressure applied through said carriage to said member is relieved to move said member outwardly of said case to free said carriage for re-tractile movement.
